By his Attorney
Clarence G. Campbell

UNITED STATES PATENT OFFICE.

HARRY C. D'ANNUNZIO, OF ROCHESTER, NEW YORK, ASSIGNOR TO ROSENBERG BROS. & COMPANY, OF FASHION PARK, ROCHESTER, NEW YORK, A CORPORATION OF NEW YORK.

GARMENT-SLEEVE.

1,278,310.

Specification of Letters Patent. Patented Sept. 10, 1918.

Application filed December 3, 1917. Serial No. 205,062.

To all whom it may concern:

Be it known that I, HARRY C. D'ANNUNZIO, a citizen of the United States, residing at Park avenue, Rochester, in the county of 5 Monroe and State of New York, have invented certain new and useful Improvements in Garment-Sleeves, of which the following is a specification.

My invention relates to an automatically 10 collapsible extension seam for the sleeves of garments and more particularly to sport coats which require a sleeve with free action.

There has been a great demand for jackets or coats for men which are adapted to be 15 worn while playing golf, tennis or other sports requiring the free action of the arms or shoulders at all times. In order to make garments conforming to these requirements, it has been necessary heretofore to use much 20 additional material, both in the material of the garment and the linings in order to obtain a garment which permits the shoulders and arms to move freely without any binding at the arm holes. This has resulted in 25 the manufacture of garments adapted to such requirements often having ungraceful lines and being unsuited for wear, except while engaging in one of the sports. These garments also contain a large amount of waste 30 material because of the necessity of their having easy flowing lines all over in order that there may be free play to the motion of the shoulders and arms. The Government has found it necessary to ask that manufacturers curtail needless waste of materials 35 during war times.

This invention not only overcomes the difficulty of poor style in sport garments by 40 making it possible to have neat fitting lines in an outer garment with all of the free action required by the shoulders and arms, but also does away with the unnecessary waste in materials found in the ordinary sport garment although retaining all of the 45 required free action of the sport garment.

Referring to the drawings, Figure 1 is a rear elevation of a sport garment embodying my invention. Fig. 2 is a top plan view of 50 an undersleeve having an extension member. Fig. 3 is the same as Fig. 2 with a tape stitched in position with the lower end being broken away. Fig. 4 is a cross section on the line 4-4 in Fig. 3. Fig. 5 is the same as Fig. 3, but with the extension member folded 55 back on the line of the tape and then back

on itself, showing in dotted outline the extension member as folded back on itself and stitched at one end. Fig. 6 is a cross section on the line 6-6 of Fig. 5. Fig. 7 is the same as Fig. 5, but shows the final stitching and 60 also the elastic member in dotted outline. Fig. 8 is a bottom plan view of the undersleeve, as shown in Fig. 7. Fig. 9 is two cross sections on the line 9-9 of Fig. 8, showing the normal and extended positions 65 of the extension seam.

In the drawings 10 is an undersleeve of a man's coat having an extension member 11 cut therewith, a tape 12 is stitched along the edge where the extension member 11 70 joins the undersleeve 10. The extension member 11 is turned back on the tape 12 at 13 and the extension member 11 is again turned back on itself at 14 so as to leave a sufficient edge 15 for the usual seam at the 75 arm hole. The extension member is stitched in this position on the line 16 at one end and longitudinally stitched along the line 17 to flatten the fold 13. To the fold 14 is secured one end of an elastic member 18 80 which is secured at the other end to the undersleeve 10 at 19. The extension member 11 is also stitched at the opposite end from the stitching 16 at 20.

After the automatically collapsible ex- 85 tension seam designated at 21 has thus been constructed, the undersleeve 10 of which it forms a part is then inserted in the garment in the arm hole 22 of the garment in the usual manner.

The left hand figure of Fig. 9 shows in cross section the collapsible extension seam 21 in its normal or closed position as shown in Fig. 1 at 23 and the other sleeve of Fig. 1 indicates the extended position of the ex- 95 tension seam 21 in actual use. The arm of the user is being swung out from the usual position as shown at 21 in Fig. 1 and is in the normal or resting position as shown in 23 of Fig. 1.

I claim:

1. In a sleeve for garments, an undersleeve section having an extension at its upper end of less width than the width of the section and doubled back to form a fold 105 that is disposed diagonally of such undersleeve section and directly at its upper margin, and an elastic element connected to the fold and disposed diagonally of the under-sleeve section.

2. In a sleeve for garments, an undersleeve section having a portion of its upper edge curved to conform to an armhole and an extension disposed at the end of the
5 curved portion and doubled back to form a fold, the free edge of said extension being disposed in substantial alinement with the said curved edge, and an elastic element connected at one end to the fold.
- 10 3. In a sleeve for garments, an undersleeve section having an extension at its upper end of less width than the width of the section and doubled back to form a fold that is disposed diagonally of said undersleeve section and directly at its upper margin, and an elastic element connected at one end to the fold and disposed diagonally of the undersleeve section, the other end of the elastic element being secured to the undersleeve section at one of its side edges.
- 15 4. In a sleeve for garments, an undersleeve section having a portion of its upper edge curved to substantially correspond to an arm-hole and an extension disposed at 25 the end of the curved portion and doubled back to form a fold, the free edge of said extension being disposed in substantial alinement with the said curved edge, and said fold being disposed diagonally of said undersleeve section and directly at its upper margin, means securing the ends of the fold to the undersleeve section, and an elastic element connected at one end to the fold and disposed diagonally of the undersleeve section, the other end of the elastic element being secured to the undersleeve section at one of its side margins.
- 20 In testimony whereof, I affix my signature in presence of two witnesses.

HARRY C. D'ANNUNZIO.
